UNITED STATES PATENT OFFICE.

ISAAC E. MOODY, OF NORTHAMPTON, MASSACHUSETTS.

MANUFACTURE OF CUTLERY HANDLES.

SPECIFICATION forming part of Letters Patent No. 359,883, dated March 22, 1887

Application filed October 19, 1885. Serial No. 180,279. (No model.)

To all whom it may concern:

Be it known that I, ISAAC E. MOODY, a citizen of the United States, residing at Northampton, in the county of Hampshire and State 5 of Massachusetts, have invented new and useful Improvements in Hollow Metallic Handles, of which the following is a specification.

This invention relates to metallic handles; and it consists in an improvement in the art 10 of making such handles for knives and similar articles, substantially as hereinafter described and claimed.

In the drawings forming part of this specification, Figure 1 is a side elevation of a table-knife having a hollow handle applied thereto 15 constructed according to my invention. Fig. 3 is a plan view of the forged handle as it appears before it is finished and attached to the knife. Fig. 4 is a transverse section of the handle, Fig. 3, on line xx . Fig. 2 is a similar view to Fig. 1, but showing a handle adapted to be attached to a tang on the knife. Fig. 5 is a side elevation, and Fig. 6 an end view, of a cylindrical bar of metal from which the hollow handle is made. Fig. 7 is a longitudinal section of the bar, Fig. 5, after the latter has 20 been bored out, making it a hollow cylinder with a solid end. Figs. 8 and 9 are similar views to Fig. 7, but showing sectional views of the tang-plugs in their ends. Fig. 10 illustrates a tang-plug in plan view and in side elevation.

In the drawings, h' , Fig. 1, represents in a longitudinal sectional view the above-mentioned improved hollow handle, having the solid butt e , which is integral with or of the same piece of metal as the sides or shell of the handle; and the tang-plug c , having the tang o thereon, is secured in the open end of the handle by drop-forging at the same time that the required form is given to the handle, as 35 shown in Figs. 1, 3, and 4, and as hereinafter described. The tang o is screw-threaded, and the bolster (shown in section) of the knife n is 40 tapped to coincide with the said screw on the tang, and the handle is thereby screwed to the bolster, the face of the latter and the adjoining end of the handle being finished in the same plane or true to each other, and thereby insuring a perfectly-tight joint between them 45 when screwed together, as shown.

The handle h to knife m , Fig. 2, is made in the same manner in all respects as said handle h' , excepting that in place of the tang-plug c the plain cylindrical plug d is secured in the open end of the handle by the means above described, by which said tang-plug is therein secured. The plug d is employed only when it is found preferable to form a tang, z , on the bolster of the knife, and in such cases the plug d is drilled and tapped, so that the handle h may be screwed onto the screw-threaded tang z , and thus the handle be secured to the knife. Either one of the above methods of attaching the handle to the knife is practicable; but that shown in Fig. 1 is the most desirable, because it obviates puncturing the plug and leaves an unbroken wall around the chamber within the handle.

The method of making the above-described handle is as follows: To produce a handle whose finished surface shall partake of the characteristics of the surface of the finished steel knife as far as possible, suitable steel, in the form of a short cylinder, a , Fig. 5, is employed, 70 said piece a being about the length of the handle to be made therefrom. The steel piece a is first drilled out and converted into a tube or hollow cylinder, b , having the solid end e . The metallic tang-plug c is then inserted in the 75 open end of tube b , as shown in Fig. 8, and said parts are together heated to a proper red or forging heat, or to a welding one, and are submitted to the action of suitably-formed dies in an ordinary drop-press, whereby they are 80 forged by a single blow of the latter to the form shown in Figs. 3 and 4. The tang-plug c and the open end of the tube b are thus by heat and pressure solidly united and secured one to the other, hermetically closing said open 85 end of the tube b , which thus becomes the tang end of the handle h' . By the said action of the drop-press on the pieces b and c the handle is 90 completely formed, and to finish it it is only necessary to remove the forging-fins x , cut a screw-thread on the tang o , face the tang end of the handle, and polish the latter.

By forming the handle h' under heat and pressure, as aforesaid, the open end of the tube b , from which the handle is made, and the said 95 tang-plug are so solidly welded together that the resultant product is a hollow handle which,

(No Model.)

W. NIEHOFF.
TREE PULLER.

No. 359,884.
